(57) **CLAIM**

The ornamental design for a toy train track connector as shown and described.

DESCRIPTION

FIG. 1 illustrates a perspective top view for a toy train track connector.

FIG. 2 illustrates a top view of the toy train track connector of FIG. 1

FIG. 3 illustrates a bottom view of the toy train track connector of FIG. 1.

FIG. 4 illustrates a left side view of the toy train track connector of FIG. 1.

FIG. 5 illustrates a right side view of the toy train track connector of FIG. 1.

FIG. 6 illustrates a front view of the toy train track connector of FIG. 1; and,

FIG. 7 illustrates a rear view of the toy train track connector of FIG. 1.

The broken lines immediately adjacent to the shaded areas depict the bounds of the claimed design, while all other broken lines are directed to environment. The broken lines form no part of the claimed design.

1 Claim, 5 Drawing Sheets
